[57] **CLAIM**

The ornamental design for a two-way portable communication device, as shown and described.

DESCRIPTION

FIG. 1 is an isometric view of a two-way portable communication device showing our new design;
FIG. 2 is a front elevational view thereof;
FIG. 3 is a left elevational view thereof;
FIG. 4 is a right elevational view thereof;
FIG. 5 is a top plan view thereof;
FIG. 6 is a bottom plan view thereof; and,
FIG. 7 is a rear elevational view thereof.
